UNITED STATES PATENT OFFICE.

WILBUR E. HOLLOWBECK AND WILLIAM R. GRAY, OF LENTNER, MISSOURI.

ENGINE-TESTER.

1,311,228.

Specification of Letters Patent. Patented July 29, 1919.

Application filed March 1, 1919. Serial No. 230,023.

To all whom it may concern:

Be it known that we, WILBUR E. HOLLOWBECK and WILLIAM R. GRAY, citizens of the United States, residing at Lentner, in the 5 county of Shelby and State of Missouri, have invented certain new and useful Improvements in Engine-Testers, of which the following is a specification.

This invention relates to measuring instruments, and especially to pressure gages for cylinders and the like; and the object of the same is to produce a tool whereby the close fit of a piston within a cylinder or of a valve within its seat may be tested accurately rather than by guess work.

The invention consists in details hereinafter more fully described and claimed and as shown in the drawings wherein

Figure 1 is a plan view of parts of a cylinder casting with the heads of the cylinders removed showing this tool applied and ready for use.

Fig. 2 is an enlarged side elevation of the tool itself, with the cup partly broken away, 25 and

Fig. 3 is a bottom plan view thereof.

The engine casting E in Fig. 1 has an opening C (here exposed by the removal of the cap plate) which constitutes one of the 30 cylinders and contains a piston as usual. This casting also has an opening in which is mounted the valve, but both of these are hidden by the tool shown in plan view as covering the same. Said tool comprises a 35 cup 1 in the shape of a cylinder closed at its upper end and open at its lower end where it is surrounded by an outstanding shoulder 2, and in the bottom of the shoulder is a rubber ring or gasket 3. A gage 4 40 communicates with the upper end of the cup, and a nipple 5 with one side thereof, the nipple being of such form that it can be connected with an ordinary hand pump for supplying air under pressure to the interior 45 of the cup. Within the latter is a coiled expansive spring 6 secured at its upper end to the head of the cup and normally projecting below the lower end of the same so as to rest upon the valve and hold it to its seat, 50 when this tool is applied for testing a valve.

For holding the cup in position on the casting E we make use of a yoke 10 forked at one end as at 11 and the tips of the fork-arms having toes 12 adapted to rest on the 55 shoulder 2 as best seen in Fig. 2. The body of the fork has a longitudinal slot 13 through

which passes a screw 14 whose head 15 rests on a washer 16 above said body, the threaded portion of said screw taking into one of the threaded openings in the casting in a 60 manner which will be clear. The remote or outer end of the body is provided with a downturned foot 17. This foot rests upon the casting at an appropriate point, and when the screw is passed down through the 65 slot and engaged with one of the holes in said casting, it is obvious that by setting the screw, the toes are caused to bear downward on the shoulder 2 so that the gasket 3 is compressed on the face of the casting 70 around the opening in which is situated the valve, for instance.

It is quite obvious that by making the device in sizes or larger than herein shown, it could be utilized for testing the close fit of 75 a piston in a cylinder instead of a valve within its seat.

In use, after the cup has been applied as suggested above, a pump is attached to the nipple 5 and air is pumped into the cup, the 80 pressure being indicated on the gage 4. Now this is allowed to stand, and if the air slowly leaks out of the cup through the article being tested, such leakage will be indicated by the movement of the hand on the gage. If, 85 on the other hand, after a reasonable time there is little or no leakage, as shown by the gage, it is reasonable to assume that the fit of the piston within the cylinder or the valve within its seat is as tight as necessary for 90 successful operation. Thus the engine can be tested reliably and without any guesswork, after which the tool is removed and used in another place or laid aside for subsequent use. 95

The foregoing description and the drawings have reference to what may be considered the preferred or approved form of our invention. It is to be understood that we may make such changes in construction and 100 arrangement and combination of parts, materials, dimensions, et cetera, as may prove expedient and fall within the scope of the appended claims.

Having thus fully described our invention, what we claim as new and desire to secure by Letters Patent is:—

1. The herein described engine tester comprising a cup having a gasket around its mouth, an air pressure gage supported by 110 said cup and communicating with the interior thereof, a nipple also communicating

with said interior for permitting the admission of air under pressure, and means engaging the cup adjacent the mouth thereof for pressing the mouth of the cup upon an article over the element therein to be tested.

2. In an engine tester, the combination with an inverted cup having an external shoulder around its open lower end, an air gage communicating with its closed upper 10 end, and means for admitting air under pressure to its interior; of a yoke having a longitudinal slot in its body and a down-turned foot at one end, its other end being forked and the fork-arms having down-turned toes bearing on said shoulder and retaining means for releasably connecting said yoke to the support.

3. In an engine tester, the combination with an inverted cup having an external 20 shoulder around its open lower end, an air gage communicating with its closed upper end, and means for admitting air under pressure to its interior; of a yoke having a longitudinally slotted body, forked at one 25 end to pass astride said cup and bear on its shoulder, and a screw passing down through said slot in the body and adapted to engage with the article being tested.

4. In a testing tool for engine valves, the 30 combination with an inverted cup having a gasket surrounding its open lower end, a gage in its upper end, means for admitting compressed air to its interior, and a spring carried by and within said cup for holding 35 the valve on its seat; of clamping means for fastening said cup down upon the engine casting over the valve chamber, for the purpose set forth.

5. In a testing tool for engine valves, the 40 combination with an inverted cup having a gasket surrounding its open lower end, a gage in its upper end, means for admitting compressed air to its interior, and a spring carried by and within said cup for holding 45 the valve on its seat; of a yoke having a downturned foot at one end and its other end forked and adapted to pass astride said cup and rest on its shoulder, and a screw passing through said yoke between its ends, 50 for the purpose set forth.

6. In an engine tester, the combination with an inverted cup having an external

shoulder around its open lower end, a gasket carried by said shoulder, an air gage communicating with the closed end of said 55 cup, and means for admitting air under pressure to its interior, of a yoke having a longitudinally slotted body, forked at one end to pass astride said cup and bear upon said shoulder, and a set screw passing through 60 said slot in the body and adapted to engage with an article being tested.

7. In an engine tester, the combination with an inverted cup having an external 65 shoulder around its open end, an air gage communicating with said cup, means for admitting air under pressure to said cup, of a yoke having a longitudinally slotted body, forked at one end to pass astride said cup and bear upon its shoulder, and a set screw 70 passing through said slot in the body and adapted to engage with an article being tested.

8. In an engine tester, the combination with an inverted cup having an external 75 shoulder around its lower end provided with a gasket, an air gage communicating with the closed end of said cup, a spring carried by and within said cup for holding a valve on its seat, and a nipple for admitting air 80 under pressure into said cup; of clamping means for engaging said shoulder for fastening said cup upon a support over a valve chamber.

9. In a testing tool for engine valves, the 85 combination of an inverted cup having a shoulder at its lower end, an air gage connected to said cup, means for admitting air under pressure to said cup, of a yoke including a slotted body which is forked at one 90 end to pass astride said cup, said forked end having downturned toes, to engage said shoulder, the remaining end of said body having a downturned foot to engage a support, and a set screw passing through said 95 slotted body to firmly clamp said yoke in a set position.

In testimony whereof we affix our signatures in presence of two witnesses.

WILBUR E. HOLLENBECK.

WILLIAM R. GRAY.
